United States Patent Office

Des. 211,289
Patented June 4, 1968

211,289

CAKE COVERING

Paul Langsam, 605 N. Sweetzer Ave.,
Los Angeles, Calif. 90048

Filed May 15, 1967, Ser. No. 7,135

Term of patent 14 years

(Cl. D59—2)

Fig. 1

Fig. 2

FIG. 1 is a top plan view of a cake covering showing my new design; and

FIG. 2 is a bottom perspective view thereof.

The essential features of my design reside in the full line disclosure.

I claim:

The ornamental design for a cake covering, substantially as shown and described.
